UNITED STATES PATENT OFFICE.

WALTER M. REASON, OF PONTIAC, MICHIGAN.

SHOE-SHINING MACHINE.

1,147,816.

Specification of Letters Patent. Patented July 27, 1915.

Application filed September 5, 1911. Serial No. 647,568.

To all whom it may concern:

Be it known that I, WALTER M. REASON, a citizen of the United States of America, residing at Pontiac, in the county of Oakland and State of Michigan, have invented 5 certain new and useful Improvements in Shoe-Shining Machines, of which the following is a specification, reference being had therein to the accompanying drawings.

This invention relates to shoe shining machines and more especially to an arrangement thereof whereby the process of dressing a shoe is automatically performed by means which are simple, effective and positive in action.

[15 The invention consists of the matters hereinafter set forth, and more particularly pointed out in the appended claims.

In the drawings, Figure 1 is a view partially in side elevation, and partially in section, of a shoe dressing machine that embodies features of the invention; Fig. 2 is a plan view, partially in section of the machine; and Fig. 3 is a view partially in elevation and partially in transverse section of the machine.

Referring to the drawings, a substantially rectangular casing 1 of suitable design and material, forms a platform with a seat 2 thereon for the user and a pair of depending bracket pedals 3 in front of the seat and below an opening in the casing top 4 from which they are suspended.

A carriage 5 is longitudinally reciprocable in the casing on suitable guides 6. A motor 7 mounted on the carriage has a main shaft 8 operating a gear train consisting of a gear 9 intermediate gear 24 and follower pinion 11, and a gear train comprising 30 a gear 10 and follower pinion 14. The follower pinion 11 of the forward train is rotatable on a worm shaft 12 unless locked to rotate the latter by means of a clutch 13. Similarly a follower pinion 14 of the train 40 10 is rotatable on the worm shaft unless locked thereto by the clutch 13 in which instance the worm shaft is driven in opposite direction. A worm 15 on said shaft meshes with a worm wheel 16 having screwthreaded 50 engagement with a shaft 17 mounted in the casing 1 parallel to the guides 6. It is to be understood that suitable provision to prevent endwise movement of the worm wheel relative to the carriage is provided, as for 55 example, by a suitable thrust bearings, not shown.

An upright spindle 18 on the carriage 5 between the bracket pedals 3 extends from a spider 19 having horizontally journaled idler rolls 20. A friction drive shaft 21 is journaled at one end in a suitable bearing 22 of the spider and also in an outboard bearing 23 on the carriage. The gear 24 operates this shaft from the motor main shaft. A friction disk 25 is journaled on the spindle 18 to ride on the idlers 20 and a friction drive pulley 26 secured to the shaft 21, the disk being designed to clear the shaft 21 and the driving connection of the latter. A turn-table 27 is journaled on the spindle 18 above and in parallel relation to the friction disk 25 and below the bracket pedals 3. A pair of cleaning brushes 28 are mounted on upright shafts 29 rotatable in bearing sleeves 30 whose lower portions are reciprocable in suitable ways on a guide plate 31 on the turn-table, suitably disposed springs yieldingly holding the brushes together. Flexible shafts 33 couple the lower portions of the upright shafts 29 with an arbor indicated at 34 of a friction roll 35 that is mounted in a hanger 36 to travel in rolling contact with the upper face of the disk 25. This pair of brushes is disposed in the turn-table so that when the latter is in initial position they are in substantial alinement with and in front of one of the pedals 3. At this time also a spring latch 37 pivoted on the carriage 5 is adjacent to a notch 38 in the margin of the turn-table so that as 90 soon as the carriage moves rearwardly away from a trip or detent 39 mounted on the casing 1, said latch will engage the notch and hold the table against turning.

A pair of filler brushes 40 are mounted in 95 yielding contact in a guide block 41 on the turn-table, and are driven similarly to the cleaning rolls 28 through flexible shafts 42 and a friction roll 43 in operative contact with the plate 25. A third pair of brushes 100 44 for applying blacking, are likewise mounted on a block 45 and are driven through similar connections from the disk 25. A fourth pair of brushes 46 mounted in a slide block on the turn-table are likewise operated from the disk 25 through connections corresponding to those of the other brushes. The pairs of brushes are so disposed in relation to each other that rotation of the turn-table until checked by the engagement of the latch 37 with properly spaced notches 47 on the table brings them 110

successively in front of and in alinement with each of the pedal shafts 3.

A suitably disposed shifting lever 48 pivoted on the frame 5 operates the clutch 13, 5 movement one way locking the pinion 11 to the worm shaft 12 and movement in the other way securing the pinion 14 to said shaft. When the lever has been thrown to cause the carriage to move in one direction 10 and it approaches the limit of motion in that direction, said lever is brought into contact with a suitably disposed stop 49 on the casing which swings the lever and moves the clutch out of engagement with one pinion 15 and into engagement with the other, thus reversing the motion of the carriage. A similar stop 50 performs the same office when the carriage reaches the opposite limit of its reciprocation. The momentum of the parts is 20 sufficient to carry the clutch and the lever that shifts it, through the neutral position.

A horizontal shaft 51 is journaled across the casing in bearings 52 that are reciprocable in upright ways 53 of suitable brackets 25 on the carriage, a spring 55 properly disposed in each bracket holding the shaft bearings normally at the lower ends of the ways. A pair of cylindrical brushes 56 each in substantial alinement with a pedal 3 30 when in initial position, are secured on a sleeve 57 reciprocable on and rotatable with the shaft 51. A spring 58 around the shaft in compression between the end of the sleeve 57 and one of the bracket bearings 52 35 normally holds the sleeve with the brushes 56 alined with the pedals. These brushes 56 are used for cleaning and applying dressing to a shoe carried under them by the forward movement of the pedals 3. A polishing brush 59 on the sleeve 57 adjacent each cleaning brush 56, is moved into alinement with its pedal when the carriage has gone forward and the turn-table is rotated to bring a stop 60 thereon into engagement 40 with a shifting finger 61 supported by the shaft 51 and operatively connected to but held in any suitable manner against rotating with the sleeve 57 to move the same along its shaft and hold it in the position to which it 45 is moved until the further rotation of the table releases the finger. The shaft 51 is conveniently driven from the transverse shaft 21, as by pairs of bevel gears 62 and a shaft 63. 50

55 The brushes 40 are supplied with a filler by an appropriate mechanism not claimed or described herein, the brushes 44 are likewise furnished with blacking by appropriate means that do not form a part of this invention, and as before stated, the brushes 56 are likewise supplied with filler and blacking.

In operation, the user places his feet upon the pedals, the brushes being in the position 60 shown in Fig. 2 and the motor is started

preferably by dropping a coin into a coin controlled switch. The clutch being in forward position, the carriage and turn-table move toward the pedals, the latch 37 dropping into the registering notch 38 and locking the turn-table so that the rotating friction disk 25 drives the friction roll 35 and rotates the brushes 28, simultaneously, of course, turning the brushes 40, 44 and 46 which, however, are not in operative relation to the pedal. The brushes 28 clean the sides and heel of the shoe on the adjacent pedal 3, the toe of the shoe underrunning the horizontal brush 56. As the carriage reaches its backward limit of motion the shifting lever encounters the stop on the casing and reverses the clutch. As the carriage reaches its initial position the latch 37 is drawn out of the turn-table notch and the friction disk 25 draws the turn-table 80 around with it until the brushes 28 are in line with the second pedal 3 and the brushes 40 with the first pedal 3. This turning movement takes place just prior to the shifting of the clutch and the reversal of movement of the carriage, the stop 39 for the latch being accurately positioned relative to the pin 50 to release the turn-table at just the proper moment relative to the moment of reversal. Thereafter the movement of the carriage is repeated, until the polishing brushes are in line with the pedals at which point the rotation of the turn-table and the engagement of the lug 60 with the arm 61 has forced the sleeve on the shaft of the 100 horizontal brushes over and brought the toe polishing brushes in line with the pedal. As long as the turn-table is locked the friction disk operates the brushes and when the turn-table is released the friction disk 105 swings it around without driving the brushes, as the turn-table rotates more easily than do the several shafts and the flexible connections of the brush mechanism.

One feature of the invention is the compactness and simplicity of the brush driving and carriage moving mechanism which when once adjusted and properly timed needs no further attention. While the friction drive is preferable as it is comparatively noiseless and is a safeguard against any possible injury to the user, gears may be substituted if desired and other changes in the details made.

Obviously changes in the arrangement and details of construction may be made without departing from the spirit of the invention and I do not care to limit myself to any specific form of arrangement of parts.

What I claim is:—

1. In a shoe shining machine, a casing having a pair of stationary pedals, pairs of rotatable brushes in substantially the plane of the pedals revoluble on a common axis and reciprocable past the pedals, the brushes

- passing on both sides thereof when reciprocated means adapted to alternately rotate the brushes on their several axes and revolve the pairs on the common axis and means to reciprocate the pairs past the pedals alternately with the motion of revolution.
2. In a shoe machine, a pair of stationary pedals, sets of rotatable brushes in substantially the plane of the pedals, means for revolving the pairs of brushes around the pedals, means for driving the revolving means adapted to rotate the brushes on their several axes when the revolving means is stationary and means to reciprocate the pairs past the pedals alternately with the motion of revolution.
3. In a shoe shining machine, a pair of stationary pedals, sets of rotatable brushes revolvable around the pedals, means for revolving the sets of brushes around the pedals, means for rotating the brushes on their axes, means for reciprocating each set of brushes past a pedal and means for intermittently arresting the revolutions of the brush sets.
4. In a shoe shining machine, a casing having a pair of stationary pedals, a carriage reciprocable in the casing past the pedals, a turn-table intermittently rotatable on the carriage, pairs of rotatable brushes on the turn-table adapted to be brought into longitudinal alinement with the pedals by the rotation of the turn-table, means on the carriage for driving the turn-table and rotating the brushes when the turn-table is stationary, and means for reciprocating the carriage in the casing, each pair of brushes embracing the pedals during the reciprocation of the pair.
5. In a shoe shining machine, a casing having a pair of stationary pedals, a carriage reciprocable in the casing past the pedals, a friction disk rotatable on the carriage in a vertical axis below the pedals, a

turn-table rotatable on the same axis above the disk, means for intermittently checking the rotation of the table pairs of rolls rotatable on vertical axes on the turn-table in substantially the plane of the pedals and friction rolls journaled on the turntable in rolling contact with the disk and operatively connected to each brush to rotate the latter.

6. In a shoe shining machine, a casing having a pair of stationary pedals, a carriage reciprocable in the casing, a motor on the carriage, driving mechanism operated by the motor for reciprocating the carriage, a friction disk rotatable on the carriage on an axis transverse to its path of motion driven by the motor, a turn-table rotatable on the carriage parallel to the friction disk, friction rolls journaled on the turn-table in contact with the disk, pairs of upright shafts yieldingly mounted on the turn-table, each shaft being driven by one of said friction rolls, a brush on each shaft, means yieldingly forcing the brushes of each pair together, means adapted to lock the turn-table from turning when the carriage is reciprocating, and means for tripping the table locking means when the carriage is in initial position.

7. In a shoe shining machine, a casing having a pair of stationary pedals, pairs of rotatable brushes, an intermittently rotatable brush support adapted to revolve the brushes around the pedals, means for rotating the brush support, means adapted to rotate the brushes when the support is held against rotation, and means for reciprocating the support.

In testimony whereof I affix my signature in presence of two witnesses.
